UNITED STATES PATENT OFFICE

MILTON H. BALLARD, OF BEVERLY, MASSACHUSETTS, ASSIGNOR TO UNITED SHOE MACHINERY CORPORATION, OF PATERSON, NEW JERSEY, A CORPORATION OF NEW JERSEY

SHOE-PRESSING MACHINE

Application filed May 2, 1927. Serial No. 188,247.

This invention relates to machines for applying pressure to the bottoms of boots and shoes, and is illustrated herein as embodied in a heel-seat forming machine arranged to apply molding pressure to the heel-seat portions of shoes to prepare the shoes for the reception of wood heels.

In the manufacture of shoes to which wood heels are to be applied, it is usual to trim surface stock from the heel-seat portions of the soles of the shoes by beveling the edges of the heel-seat portions of the soles to bring them to a shape approximately complementary to that of the attaching surfaces of the wood heels which are to be attached. In order to provide a solid heel-seat and to cause the heel-seat portion of the sole of the shoe to contact over the greater portion of its area with the attaching surface of the wood heel which is to be attached, heel-seat forming or molding machines have come into use. A heel-seat forming machine is commonly provided with a mold or a pair of molds readily changeable in accordance with the size and shape of the shoe to be operated upon, a work support or a pair of work supports, and means for causing relative movement of each mold and the corresponding work support so as to apply a heavy molding pressure to the heel-seat portion of a shoe mounted upon a last carried by the work support.

An object of this invention is to provide, in connection with mechanism for applying heavy molding pressure and improved measuring means adapted to be incorporated in a heel-seat forming machine and by virtue of which pressure-applying movements of the pressure-applying means will be uniformly effective irrespective of variations in the heights of the lasts of different shoes operated upon. With this object in view, the illustrated machine is provided with a shoe support, a heel-seat forming mold or die, and mechanism for moving the die preliminarily into contact with the heel-seat of the shoe, the said mechanism being arranged to hold the die against regression from any point to which it may be moved and to be released at will to permit the adjustment of the shoe and die if their initial adjustment is not satis-

factory. The die and shoe support are, as usual in machines of this type, relatively adjustable to locate the die and heel-seat in proper relative position. After proper relative location of the heel-seat and die has been effected, a predetermined pressure is applied to the shoe support to form the heel-seat, the die being held against regressive movement during the application of the heel-seat forming pressure. In the illustrated machine, the mold or die is mounted on a carrier which is yieldingly upheld and is moved toward the shoe by means of a member of varying thickness arranged to be inserted between surfaces formed respectively on the machine frame and on the die carrier. The member is illustrated as a wedge arranged for operation manually by a hand lever and if of relatively small angle so as to avoid danger of the wedge slipping when the forming pressure is applied to the shoe. The small angle of the wedge also gives mechanical advantage to the operator in applying preliminary pressure to the die. In order that the wedge may be automatically retracted when the pressure is released, the illustrated organization is provided with a spring that tends constantly to retract the wedge, the friction of the wedge against the cooperating surfaces of the die carrier and frame being sufficient to hold the wedge in place against the tension of the spring after the preliminary pressure is applied.

As usual in machines of this type, the work support is arranged to swing into and out of position under the die and has its last pin arranged for adjustment in the plane of the heel-seat so that the heel-seat of a shoe placed upon the support may be located under the die in proper relation thereto. With the organization illustrated, the die may then be brought down by operation of a hand lever into contact with the heel-seat. The position of the shoe relatively to the die is then shifted as determined by the judgment of the operator, the die being released, if necessary, by reverse movement of the hand lever. After the heel-seat and die have been properly located, the pressure of the die is increased by movement of the wedge to prevent accidental

displacement of the shoe, and the heel-seat forming pressure effected by movement of the work support is then caused to take place. For this purpose, in the illustrated machine, 5 a treadle having a lost-motion connection with a clutch stop lever is provided, preliminary movement of which, permitted by the lost motion, may be utilized to apply upward pressure to the work support through the 10 yielding connection. This additional preliminary pressure of the work support is useful in maintaining the shoes and die in proper relationship and preventing accidental slipping of the wedge in case the operator failed 15 to apply sufficient force to the hand lever to secure the wedge in position. It is to be understood, however, that the connections from the treadle to the work support may be omitted and the treadle utilized solely for 20 tripping the clutch.

In order to avoid as much movement of the die by the wedge as would be necessary to take care of the various heights of lasts used in the various sizes of shoes, a height 25 adjustment for the work support is preferably provided. The operator uses this adjustment whenever necessary to bring the heel-seat of the shoe into close relation to the die before operating the wedge to take up the 30 remaining distance between the die and shoe and apply the preliminary pressure.

With these and other objects and features in view, the invention will be described in connection with the accompanying drawings 35 and pointed out in the appended claims.

In the drawings,—

Fig. 1 is a side elevation of a machine embodying the present invention;

Fig. 2 is a plan view of the top of the machine;

Fig. 3 is a front elevation of the parts shown in Fig. 2; and

Fig. 4 is a side elevation of the upper part of the machine from the side opposite to that shown in Fig. 1.

The illustrated machine, in its general organization, is similar to that disclosed in application Serial No. 36,922, filed June 13, 1925, by R. E. Duplessis, and in application Serial 50 No. 112,279, filed May 28, 1926, by Ballard and Seely. It is to be understood that the present invention may be utilized in connection with either of the general organizations disclosed in these prior applications, though, 55 for convenience of illustration merely, the construction herein shown is more nearly similar to that disclosed in the earlier application, to which reference may be had for explanation of parts not herein fully described.

In the drawings, the numeral 10 indicates the frame of the machine in which is mounted a shaft 12. On the shaft is an eccentric 14 which operates through an eccentric strap 16 60 to straighten a toggle 18, 20, to which the

strap is connected by a pin 17. The upper link 18 of the toggle is connected to a sliding post 22, and the lower link 20 is connected to a plunger 24 which slides in a cylindrical chamber 26 on the frame and is sustained by 70 a heavy spring 28. Between the eccentric 14 and a continuously rotating gear 30 is a half-revolution clutch which is tripped by operation of a stop lever 32. A rod 34 has a lost-motion connection at its upper end with the lever 32 and at its lower end is connected to a treadle 36 pivoted to the frame at 38 and held in elevated position by a tension spring 39. On the rod 34 is a fixed collar 40 between which and the bifurcated arm of a lever 42 75 is a spring 44. The lever 42 is pivoted at 46 and has its other arm connected by a link 48 to the post 22. Depression of the treadle 36, therefore, acts through the spring 44 to lift upwardly on the post 22 until the lost-motion connection between the rod 34 and the lever 32 is taken up, whereupon the clutch will be tripped. A slight upward movement of the post 22 is permitted because the hole in the eccentric strap 16 through which the pin 17 passes is slightly elongated. The gear 30 is continuously operated through suitable 80 gearing connecting it to an electric motor 50.

Secured to the upper portion of the framework 10 is a rearwardly tilted frame 52 held by heavy rods 54 to the frame 10. Secured by the rods 54 to the frame 52 is a head 56 in which a die carrier 58 is mounted for sliding movement, the axis of the die carrier being in longitudinal alinement with the post 22. The portion of the die carrier which passes 90 through the head 56 is cylindrical and, to prevent it from turning and maintain it in a raised position, the upper end of the carrier is slotted (Fig. 4) to receive a pin 60 which 100 passes through the head and the slot in the carrier 58. A screw 62 passes freely through the pin 60 and is threaded into the carrier 58. Between the pin and the head of the screw 62 is a spring 64 which acts to maintain the carrier 58 normally in raised position. Below the head 56 the sides of the carrier 58 are flattened, and this portion of the carrier is embraced by a long, bifurcated wedge 66, the upper surface of the wedge being perpendicular to the axis of the carrier and bearing on the head 56. The lower face of the wedge is inclined and engages inclined surfaces formed on lateral projections 68 of the carrier. The angle of the wedge is made enough 110 less than the angle of repose when the wedge is subjected to the greatest possible pressure by the machine so that there will be no danger of the wedge slipping when the power pressure is applied to the shoe. The rear end of the wedge 66 is guided for rectilinear movement in a depression formed in a supporting plate 70 and is operated by a hand lever 72 which is pivoted at 74 to the frame of the machine and carries on its lower side a roll 76 120 130

(Fig. 2) which enters a slot 78 formed in the wedge 66, the slot permitting rectilinear movement of the wedge as the lever 72 is swung on its pivot. To retract the wedge and maintain it in retracted position, a spring 80 is provided which is wound about the pivot 74 of the lever and has one of its ends held stationary while the other end engages a pin 82 on the lever 72, the spring being under sufficient tension to retract the wedge and hold it against a stop 84 which preferably is formed of yielding material so as to deaden the blow of the wedge against it when the wedge is retracted by its spring. Removably attached to the die carrier 58 is a die 86 (Fig. 3), the lower face of the die being shaped to impart to the heel-seat portion of the shoe a form suitable to receive the cupped heel-seat face of a wood heel.

To support the shoe, a jack of the type fully disclosed in the prior application first mentioned is provided which comprises a member 88 pivoted to the post 22 at 90 so that it may be swung into and out of a position under the die 86. Telescoping into the member 88 is a threaded member 92 upon which is a nut 94 which can be conveniently rotated to vary the height of the shoe support or jack. The member 92 supports a heel pin 96, between which and the member 92 are provided adjustments to enable the pin to be tipped and shifted so that the heel-seat of the shoe may be brought into parallelism with the face of the die which is to act upon it.

In the operation of the machine, the last of a shoe such as a turn or McKay shoe, to which a wood heel is to be attached, is placed upon the last pin 96, the heel-seat of the shoe having been previously fitted by the removal of the peripheral portion of the heel end of the sole. The operator, grasping the shoe, tips the shoe support about the pivot 90 to locate the heel-seat of the shoe longitudinally under the die 86 and locates the shoe laterally with respect to the die, as permitted by the above-mentioned adjustments provided in the work support. If the space between the heel-seat of the shoe and the die is substantial, he will operate the nut 94 to raise the shoe and bring the heel-seat into close relation to the die 86. He then grasps the handle 72 and draws it toward him, thus moving the wedge 66 forwardly and causing it to move the die carrier 58 toward the shoe, the die being held by the wedge against regression from the point to which it has been moved. If he finds that the die is not in proper relation to the heel-seat, he may withdraw the wedge by reverse movement of the handle and reposition the shoe with respect to the die and again apply, by movement of the wedge, sufficient preliminary pressure to insure that the relative positions of the die and shoe will be maintained. He then depresses the treadle to trip the clutch, incidentally applying through the

spring 44 additional pressure to the shoe. The clutch operates to connect the eccentric 14 to the continuously rotating gear to impart a half revolution to the eccentric which operates to straighten the toggle 18, 20 to move upwardly the work support with a force predetermined by the strength of the spring 28 which is tensioned by downward movement of the plunger 24 to which the lower link 20 of the toggle is pivoted. After a half revolution, the eccentric stops with the work under pressure, so to remain until the operator has similarly treated a shoe by the duplicate mechanism on the opposite side of the machine, after which the treadle will be again depressed and the eccentric 14 operated another half revolution to release the pressure on the shoe. After treatment the materials of the shoe will be sufficiently compressed so that the shoe support may be swung from under the die, even before the wedge-retracting spring 80 has time to retract the wedge and permit the die carrier to be raised by its elevating spring 64. The retraction of the wedge and elevation of the die, however, take place automatically, putting the parts in position for operation, in the manner described, on another shoe.

Having thus described my invention, what I claim as new and desire to secure by Letters Patent of the United States is:

1. A machine for forming the heel-seats of shoes for the reception of wood heels having, in combination, a shoe support constructed and arranged to present a shoe bottom up to the operator, a heel-seat die movable toward the heel-seat of a shoe on the support, means for moving the die toward the shoe with preliminary pressure and holding the die against regression from any point to which it may be moved, said means being releasable to permit repositioning of the shoe, and means operable after the preliminary pressure is applied by the die for applying final pressure to the shoe support.

2. A machine for forming the heel-seats of shoes for the reception of wood heels having, in combination, a shoe support, a die movable toward a shoe on the support, the shoe support being movable laterally relatively to the die to permit proper location of the heel-seat of the shoe relatively to the die, means for moving the die toward the shoe with preliminary pressure and for holding the die against regression from any point to which it may be moved, said means being releasable to permit repositioning of the shoe, and means operable after the preliminary pressure is applied by the die for applying a predetermined pressure to the shoe support.

3. A machine for forming the heel-seats of shoes for the reception of wood heels having, in combination, a shoe support, a die for forming the heel-seat of a shoe, a wedge for relatively moving the die and shoe support to

- apply preliminary pressure between the die and the heel-seat of the shoe and to prevent relative regression of the shoe and die, said wedge being reversely operable to release the pressure if desired to permit repositioning of the shoe, and means for applying final heavy pressure to the shoe support to form the heel-seat.
4. A machine for forming the heel-seats of shoes for the reception of wood heels having, in combination, a shoe support constructed and arranged to present a shoe placed thereon bottom up to the operator, a heel-seat die for forming the heel-seat of a shoe, means for adjusting the shoe support toward and from the die, means for moving the die toward the shoe with preliminary pressure and for holding the die against regression under heel-seat forming pressure, said means being reversely operable to release the pressure if desired to permit repositioning of the shoe, and means for applying a predetermined final pressure to the shoe support to form the heel-seat.
5. A machine for forming the heel-seats of shoes for the reception of wood heels having, in combination, a shoe support, a heel-seat die, a die carrier movable toward a shoe on the support, means comprising a member of varying thickness operating between surfaces on the die carrier and the machine frame for moving the die against the shoe to hold the shoe against accidental displacement after being positioned properly with respect to the die, and means for effecting upward movement of the shoe support to apply predetermined heel-seat forming pressure to the shoe.
6. A machine for forming the heel-seats of shoes for the reception of wood heels having, in combination, a shoe support, a die carrier movable toward and from the support, a member of varying thickness acting directly on the die carrier to move it toward the shoe and to prevent movement of the carrier away from the shoe, power means for raising the shoe support to apply heel-seat forming pressure to the shoe, and automatic means operating after the pressure on the shoe is released for withdrawing said member.
7. A machine for forming the heel-seats of shoes for the reception of wood heels having, in combination, a shoe support, a die movable toward a shoe on the support, means comprising a wedge for moving the die against the shoe to hold the shoe against accidental displacement after being positioned properly with respect to the die, and power means for effecting upward movement of the shoe support to apply heel-seat forming pressure to the shoe.
8. A machine for forming the heel-seats of shoes for the reception of wood heels having, in combination, a shoe support, a die carrier movable toward and from the support, a wedge acting directly on the die carrier to move it toward the shoe and prevent move-
- ment of the carrier away from the shoe, power means for raising the shoe support to apply heel-seat forming pressure to the shoe, and spring means operating after the pressure on the shoe is released for withdrawing the wedge.
9. A machine for forming the heel-seats of shoes for the reception of wood heels having, in combination, a shoe support, mechanism for raising the shoe support, a die and die carrier movable toward the shoe support, a wedge arranged to engage surfaces on the frame and the die carrier for moving the die toward the shoe and for preventing movement of the die away from the shoe, a lever by which the wedge is moved into engagement with the frame and carrier, and automatic means for withdrawing the wedge.
10. A machine for forming the heel-seats of shoes for the reception of wood heels having, in combination, a shoe support, eccentric and toggle mechanism for operating the shoe support, a die and die carrier movable toward the shoe support, a wedge arranged to engage surfaces on the frame and the die carrier for moving the die toward the shoe and for preventing movement of the die away from the shoe, a lever by which the wedge is moved into engagement with the frame and carrier, and spring means for withdrawing the wedge.
11. A machine for forming the heel-seats of shoes for the reception of wood heels having, in combination, a shoe support, eccentric and toggle mechanism for operating the shoe support, a die and die carrier movable toward the shoe support, a spring for retracting the carrier, and a wedge arranged to engage surfaces on the frame and die carrier for effecting movement of the die carrier toward the shoe support.
12. A machine for forming the heel-seats of shoes for the reception of wood heels having, in combination, a shoe support, eccentric and toggle mechanism for operating the shoe support, a die and die carrier movable toward the shoe support, a spring for retracting the carrier, a wedge arranged to engage surfaces on the frame and die carrier for effecting movement of the die carrier toward the shoe support, and a spring for retracting the wedge.
13. A machine for forming the heel-seats of shoes for the reception of wood heels having, in combination, a shoe support, power-operated mechanism for raising the shoe support, a die and die carrier movable toward the shoe support, a bifurcated wedge arranged to embrace the die carrier and to engage surfaces on the frame and die carrier to move the die carrier toward the shoe, a hand lever for operating the wedge, and means acting automatically to retract the wedge.
14. A machine for forming the heel-seats

of shoes for the reception of wood heels having, in combination, a shoe support, eccentric and toggle mechanism for operating the shoe support, a die and die carrier movable toward the shoe support, a bifurcated wedge 5 arranged to embrace the die carrier and to engage surfaces on the frame and die carrier to move the die carrier toward the shoe, a hand lever for operating the wedge, and a 10 spring acting on the lever for retracting the wedge.

15. A machine for forming the heel-seats of shoes for the reception of wood heels having, in combination, a shoe support, a die 15 movable manually against a shoe on the support with sufficient pressure to hold the shoe against accidental displacement after being positioned properly with respect to the die, means comprising a wedge of small angle for 20 operating the die to apply said pressure to the shoe, power means for effecting upward movement of the shoe support to apply heel-seat forming pressure to the shoe, and means for withdrawing the wedge after the 25 heel-seat has been formed.

16. A machine for forming the heel-seats of shoes for the reception of wood heels having, in combination, a vertically adjustable work support, a die movable manually 30 against a shoe on the support with sufficient preliminary pressure to hold the shoe against accidental displacement after being positioned by adjustment of the support into proximity to the die, means comprising a 35 wedge of small angle for operating the die to apply said pressure, and power means for effecting upward movement of the work support to apply heel-seat forming pressure to the shoe.

40 In testimony whereof I have signed my name to this specification.
